DOUBLE THROW CLAMP-TIGHT SWITCH

Arthur S. Caswell, Philadelphia, Pa., assignor to
 I. T. E. Circuit Breaker Company, Philadelphia,
 Pa., a corporation of Pennsylvania

Application May 21, 1946, Serial No. 671,172

2 Claims. (Cl. 200—170)

1

My present invention relates to switchgear, and more particularly to double throw switchgear arranged to engage the movable contact with the stationary contacts in a tight clamping arrangement in each position of the double throw switch.

Heretofore in switchgear of the knife switch type, it has been customary to provide a clamping arrangement for interengaging the movable element of the knife switch with the stationary contact. A portion of the closing movement of the switch was used to bring the movable contact or blade up into registry with the stationary contact and the remaining movement of the switch handle performed the clamping action. This type of clamping action is shown in the Scott Patent 2,246,072, assigned to the assignee of the present invention.

However, the problem becomes more complex in double throw switches where the movable contact blade has a neutral position as well as two separate contacting positions 180° apart.

Various means have been attempted to provide for adequate clamping pressure at both contacting positions of the knife blade but these have resulted in extremely complex duplicate clamping mechanisms or in having a clamped contact arrangement at one position only with the other position being subjected to only light clamping engagement.

In general, my invention contemplates an arrangement of a double throw clamp tight switch in which partial movement of the operating handle first throws the movable contact into position for engagement with one of the terminals. On further movement of the operating handle to its final position, a wedge member is operated which clamps the movable contact into engagement with its associated terminal. This same operation occurs at the opposite terminal, the wedging member again functioning to clamp the contact in engagement.

My invention specifically contemplates the utilization of a wedge member so arranged that on operation of the knife switch handle to the closed position in either direction, the wedge will be actuated to drive the bridging blades together.

Accordingly an object of my invention is to provide a novel clamp tight arrangement for a double throw knife switch.

A further object of my invention is to provide a novel wedging mechanism for effecting clamping of a double throw knife switch in either of its positions.

2

Still another object of my invention is to provide an arrangement whereby the knife switch blade is operable during one portion of the movement of the operating handle to engaging position and is operated into clamping engagement by the remaining operation of the handle.

The foregoing and many other objects of my invention will become apparent in the following description and drawings in which:

10 Figure 1 is a side view of my novel double throw knife switch.

Figure 2 is a view in perspective of my novel double throw knife switch showing the wedging element therein.

15 Figure 3 is a view in perspective showing the unclamped position of the wedge of my novel double throw knife switch.

Figure 4 is a view in perspective showing the clamped position of the wedge of my novel knife switch.

20 Figure 5 is a view corresponding substantially to that of Figure 1 showing, however, the handle in the fully closed position.

Figure 6 is a top view partly in cross-section 25 of the wedge member and its cooperating elements corresponding to the position shown in Figure 3.

Figure 7 is a view similar to that of Figure 6 with the elements corresponding to the view of Figure 4.

30 Referring now to Figures 1 and 2, my novel double throw knife switch is mounted on an insulating panel 11 to which are connected the upper stationary contact 12 and the lower stationary contact 13. Contacts 12 and 13 are mounted respectively on the ends of back connection studs 14 and 15, which pass through appropriate openings in the insulating panel 11. The terminal 17 for the movable contact member is also mounted at the front of the insulating panel 11 and is connected through an appropriate opening to its own back connection stud 18.

The knife blades 20 and 21 which form the 35 movable bridging contact are pivotally mounted on the extension 25 of the contact terminal 17.

As the handle assembly 27 is operated from the upper position to the lower position, the contact portions 21a and 20a of the knife switch are 40 rotated about from the position wherein they engage the upper stationary contact 12 to the position where they engage the lower stationary contact 13.

The handle assembly 27 consists of a pair of side 45 plates 28 and 29 which are also pivotally mounted

at the extension 25 of the central terminal 17. Plates 28 and 29 straddle extension 25 as shown, and are continued up to a point just below the point of registry of the handle with the contact member 12 in the up position or contact member 13 in the down position, at which point they are re-entrantly bent at 30, 31 and secured together to form an extension 32 which passes between the jaws of the contact member 12 or 13. A suitable handle 34 is secured to the extension 32.

The side plates 28 and 29 are provided with the registering slots 40 through which the pin 41 of the contact blade operating link 42 passes. Contact blade operating link 42 is provided with a cam roller 43 at its lower end which roller may be a compound roller as shown in Figure 2 and its upper end is secured at 44 to the lower end of tension spring 45.

The upper end of tension spring 45 is secured to the pin 46 carried between the handle plates 28 and 29.

The handle plates 28 and 29 are also provided with the registering curved parallel slots 50 through which passes the sleeve 51. Sleeve 51 is provided with a slot 52 at its lower surface and a slightly smaller parallel slot 53 at its upper surface to receive wedge 57 hereinafter described. The contact blade operating link 42 has an opening 55 through which the sleeve 51 also passes.

The opening 55 of the contact operating lever 42 has secured therein in any suitable manner the wedge 57 which, as shown, particularly in Figures 3 and 4, extends from the bottom to the top of opening 55.

The wedge 57 passes through lower slot 52 of sleeve 51 and the upper slot 53 thereof. The slots 52 and 53 are sufficiently wide to permit the wedge to move up and down in the manner hereinafter described.

As shown also in Figures 2, 3 and 4, and especially in Figures 6 and 7, the sleeve carries therein the split clamping studs 60 and 61.

Stud 61 is secured by the bolt 63 to clamping plate 64. Stud 60 is secured by bolt 65 to clamping plate 66. Studs 60 and 61 have respectively the registering re-entrant portions 68 and 69 on opposite sides of the wedge 57.

The central extension 25 from the central terminal 17 is provided with the cam surface 70 having the central front recess 71, upper curve 72, and lower curve 73.

In the neutral or open position of the switch as shown by the dotted lines of Figure 1, the cam roller 43 of link 42 is in the central recess 71 of the cam 70. Tension spring 45 acts as a centering spring to hold the handle member 27 in the horizontal position. To further ensure that the handle member 27 remains in the horizontal position, the slots 50 are provided with the matching recesses 75 which register with the lugs 76 secured to the tube 51.

The opening 80 of handle plates 28 and 29 around the center of rotation of pivot 81 mounted on extension 25 is slightly larger than the pivot 81. Accordingly, spring 45 pulls the handle 27 to the left in the horizontal open dotted line position of Figure 1 so that notches 75 engage the lugs 76 to maintain the open position.

When it is desired to close the switch to the up position of Figure 1, the handle 34 is first pulled out pulling out the handle assembly 27 and disengaging notches 75 from extension 76. The manually graspable handle 34 and the handle assembly 27 is now raised rotating about the cen-

ter 81. Since the pin 41 of link 42 is held in the slot 40, motion is transmitted to the link 42 through an appropriate roller on the pin 41 and link 42 is also rotated upwardly. Since, however, roller 43 is held in the recess 71, the upper end of link 42 moves up faster than pin 41 and hence faster than the handle assembly 27. This moves the sleeve 51 up faster than the handle assembly 27 and sleeve 51 moves rapidly toward the left in the slot 50 of the handle assembly 27 while the handle assembly is being moved up by hand. This extends the tension spring 45 and at the same time causes the contact blades 20 and 21 to move up ahead of the handle assembly 27 to contacting position.

The extension of tension spring 45 now exerts a lifting pressure on link 42 pulling roller 43 out of the depression 71 and up onto the upper surface 72 of cam 70. Spring 45 ensures that roller 43 of lever 42 will follow the cam surface.

When the contact blades 21 engage contact 12 of the upper terminal, further travel in a counter-clockwise or up direction of the handle assembly 27 forces the roller 43 to roll along the upper surface of cam 70. This forces the link 42 and the wedge 57 in the upper end thereof to rise with respect to the sleeve 51 and the slot 50.

As the wedge 57 rises, it moves from the position shown in Figures 3 and 6 to the position shown in Figures 4 and 7 spreading the re-entrant extensions 68 and 69 of the split clamp studs 60 and 61 apart. This draws together the studs 60 and 61 and the bolts 63 and 65 thereof, thus drawing together the clamping members 64 and 66.

When the handle assembly 27 has reached the full contact closing position, the wedge 57 has been moved up to the final position of Figures 4 and 7 and has as previously described fully drawn together the clamping members 64 and 66, thus clamping the bridging contact blades 20 and 21 tightly across the contact members 12 and 25.

The handle 34 is provided with a latch tip 90 which engages the latch keeper 91 at the upper terminal 12. The spring 45 causes the latch members 90 and 91 to interengage.

To open the contacts, handle 34 is first lifted to disengage latches 90 and 91 extending the spring 45 slightly for this purpose and the handle assembly 27 is then rotated downwardly. The reverse of the operation above described occurs. The initial clockwise rotation of handle assembly 27 owing to the arrangement of slot 40 and pin 41 causes the link 42 to rotate to the intermediate position shown at the upper portions of Figure 1. This, since it is the reverse of the previous operation, lowers the wedge from the position of Figures 7 and 4 to the position of Figures 6 and 3. This releases the clamps 64 and 66; and further clockwise rotation of the handle assembly 27 moves the switch blades 20 and 21 and all of the handle elements to the horizontal dotted line position of Figure 1.

The operation for engaging the contact blades 20 and 21 across contacts 13 and 25 is exactly the same. The handle assembly 27 is pulled out and moved down; the contact blades 20 and 21 first engage the stationary contact 13 and then the clamp is tightened in exactly the manner above described when the handle assembly 27 is pushed home to the vertical position. Latch 92 of the handle 34 engages the latch keeper 93 to maintain the lower contact closed position.

By this means, therefore, a simple clampable double throw knife type switch is provided with

a simplified wedging element which is actuated to clamping position both in the up and down closed position of the contacts. Complex machining or threading operations are avoided and a single wedge combined with a single split clamping stud arrangement and the actuation of the wedge by a single cam member performs the clamping operation in either closed position.

In the foregoing, I have described my invention solely in connection with a specific preferred embodiment thereof. Since many variations and modifications of my invention should now be obvious to those skilled in the art, I prefer to be bound not by the specific disclosure herein contained but only by the appended claims.

I claim:

1. In a switch mechanism, a pivotally mounted double throw knife switch blade, a pair of terminals, each of said terminals comprising a pair of jaws, a handle assembly comprising a pair of side plates pivotally mounted on the same pivot as said blade, a handle secured to said side plates, a slot in said side plates, a pin mounted in said slot, a contact operating link mounted on said pin, a camming surface, a cam follower on one end of said link and a spring extending from the other end of said link to said side plates for maintaining said cam follower on said camming surface, a pair of clamping plates, a supporting means for said clamping plates, a wedge operable in said supporting means for moving said supporting means to effect movement of said clamping plates toward and away from each other, means controlled by the movement of said handle for operating said link to drive said cam on its follower; said supporting means being responsive to the movement of said cam for operating said blade

to engage said jaws, and said link means being thereafter responsive to further movement of said handle for driving said wedge to effect axial movement of said supporting means to 5 in turn operate said clamping plates to clamp said jaws to said switch blade.

2. In a switch mechanism, a pivotally mounted double throw knife switch blade, a pair of terminals each comprising a pair of jaw blades, 10 an operating handle, a pair of clamping plates, a member for carrying said clamping plates, a wedge mounted on said member, means responsive to movement of said handle for operating said knife blade to engage one of said terminals 15 and for thereafter operating said wedge to operate said member to move said clamping plates and clamp said blade to said terminal, and means for locking said first mentioned means in either of said operating positions with said terminals and in an intermediate position.

ARTHUR S. CASWELL.
